[57] CLAIM

The ornamental design for a fuel pump canopy, as shown.

DESCRIPTION

FIG. 1 is a perspective view of a fuel pump canopy showing my new design; the broken line showing of a gasoline pump is for illustrative purposes only and forms no part of the claimed design;

FIG. 2 is a top perspective view;

FIG. 3 is an end elevational view;

FIG. 4 is a side elevational view; and

FIG. 5 is a top plan view.

FIG. 1

FIG. 2

FIG. 3

FIG. 4

FIG. 5
